CLAIM

The ornamental design for a measurement head for surgical tool, as shown and described.

DESCRIPTION

FIG. 1 is a top, front left perspective view of a measurement head for surgical tool showing our new design; FIG. 2 is a bottom, front left perspective view thereof; FIG. 3 is a top, rear left perspective view thereof; FIG. 4 is a bottom, rear left perspective view thereof; FIG. 5 is a top, front right perspective view thereof; FIG. 6 is a bottom, front right perspective view thereof; FIG. 7 is a top, rear right perspective view thereof; FIG. 8 is a bottom, rear right perspective view thereof; FIG. 9 is a front end view thereof; FIG. 10 is a rear end view thereof; FIG. 11 is a top plan view thereof; FIG. 12 is a bottom plan view thereof; and FIG. 13 is a right side elevational view thereof; and FIG. 14 is a left side elevational view thereof.

In the drawings, the broken lines show unclaimed portions of the measurement head for surgical instrument that form no part of the claimed design. The broken lines between the left and right sides of the design represent unclaimed ornamentation that form no part of the claimed design.

1 Claim, 11 Drawing Sheets
